UNITED STATES PATENT OFFICE.

MATTHEW STEEL, SR., AND MATTHEW STEEL, JR., OF GOSFORTH, ENGLAND.

BLOWPIPE.

1,093,495.

Specification of Letters Patent. Patented Apr. 14, 1914.

Application filed May 25, 1912. Serial No. 699,784.

To all whom it may concern:

Be it known that we, MATTHEW STEEL, Sr., and MATTHEW STEEL, Jr., subjects of the King of Great Britain and Ireland, residing at Gosforth, in the county of Northumberland, England, have invented certain new and useful Improvements in Blowpipes; and we do hereby declare the following to be a full, clear, and exact description of the invention, such as will enable others skilled in the art to which it appertains to make and use the same.

This invention relates to improvements in or connected with blow pipe burners which are thereby adapted to be used with carbureters, the object in view being to produce the Bunsen or blow pipe flame of various grades of intensity in temperature and extent or character of flame from carbureted air and petrol gas.

In describing our invention we will refer to the drawing accompanying this specification in which—

Figure 1 is a side elevation of a burner constructed according to our invention. Fig. 2 is a sectional view of the nozzle, and Figs. 3, 4 and 5 are detail views of disks adapted to be used within the nozzle. Fig. 6 is a sectional view of a modified form of cone shaped nozzle burner.

Behind the burner nozzle *a* we provide two pipes *b*¹ *b*² converging into one at *b* whereby the combustible gas such as carbureted air or petrol gas supplied through one, say *b*¹ is mixed with and driven forward by air supplied through the other say *b*², the united pipe *b* being about the same in bore as each of the pipes converging into it and the union taking place so near to the nozzle that all further intermixture of blast air and carbureted air takes place in the nozzle itself. At a short distance beyond this union of the two pipes *b*¹ *b*² say equal to two or three diameters the united pipe *b* enters or communicates with the chamber within the nozzle *a* which chamber may conveniently take the form illustrated in Fig. 2 or in some cases the form illustrated in Fig. 6. Provision being made by cocks *c*¹ *c*² one on each pipe *b*¹ *b*² to regulate the supply of carbureted air or petrol gas through pipe *b*¹ and blast air through pipe *b*² for the purposes required as hereinafter explained, the internal formation and arrangement of the nozzle chamber is most important it being an essential condition for attaining the proper

flame that the outside air is drawn inwardly through the orifice of the nozzle into the chamber where the combustion takes place and therefore in the opposite direction to the carbureted air or petrol gas which is leaving the chamber in a state of combustion. In the absence of some restriction of the volume of carbureted air or petrol gas passing into the combustion chamber *a*¹ the nozzle orifice would be so filled up with the escaping gases that outside air would not be drawn in; *d* is a disk for effecting this restriction by dividing off the combustion chamber *a*¹ from the mixing chamber *a*² and the necessary restriction may be effected by a central hole *d*¹. Fig. 3 perforated through the aforesaid disk *d* adjusted in area in relation to the area of the nozzle orifice, the latter being considerably the larger so that while carbureted air or petrol gas is discharged into the chamber *a*¹ as mixed with blast air in chamber *a*² in a sufficient volume to support a blow pipe flame, air is drawn in and down or along the said chamber *a*¹ in a sufficient quantity for the purpose of supporting internal combustion. But a still better result is attained by following the arrangement of holes shown in Fig. 4 that is with a tier or circle of holes provided in the disk around a central hole *d*¹ leaving an outer annular blank space between the circle of holes and the nozzle wall and an inner annular blank space between the circle of holes and the central hole, each annular space being about equal in width to the diameter of the holes or about one fourth of the radius in a 24 inch diameter nozzle, or the Figs. 3 and 4 may be taken as drawn to scale and taken as examples are found to give good results, especially Fig. 4 when using carbureted air or petrol gas which is otherwise difficult to retain in a state of flame which can be applied from the nozzle in the manner required for blow pipe purposes. In conjunction with such an arrangement of holes in the disk it is found that a good position for the disk *d*, is that shown in Fig. 2 or about one inch within the nozzle as measured from the orifice thereof.

The arrows in Fig. 2 are intended to show how the currents of air pass inwardly in a direction contrary to the outgoing mixture of gas and air issuing in streams through the disk *d* and the orifice of the nozzle, the outside air being drawn in between the said streams and the nozzle wall and thereby heated and superheated and consequently ex-

panded, thus giving additional or increased pressure and intensity to the flame issuing from the interior of the nozzle or combustion chamber.

- 5 The relative total area of the holes in the disk d being correctly adjusted to the area of the orifice of the nozzle and to the capacity of the combustion chamber the flame discharged from the burner will extend from 3 10 to 18 inches in length as required according to the force with which the mixture of air and gas is blown in. If the tendency is for the flame to show white the supply of air is too little in proportion to the supply of gas; 15 if the tendency is for the flame to go out the supply of gas is too little, and the adjustment in either case is made by turning the cocks c^1 c^2 .

The nozzle or enlargement a is preferably 20 made in parts a^3 a^4 and a^5 so that the combustion chamber part a^3 may be screwed into the intake part a^4 , and where a second disk is used to prevent back firing when the blast or bellows pressure dies down the intake 25 part a^4 is preferably screwed into the union part a^5 which latter is screwed onto the delivery end of the double pipe b .

The space between the disk d and the inlet of the nozzle called the mixing chamber a^2 is mainly useful for cushioning the 30 pressure of the mixture of gas and air pumped into the nozzle so that sudden variations in this respect are not transmitted in their full effect to the flame which would 35 be the result in the absence of such a chamber even to the extent in the case of pedal bellows of blowing the flame out. A further advantage of such a space is that a wire gauze or closely perforated disk e Fig. 5 can 40 be inserted between the primary disk d Fig. 3 or 4 and the nozzle inlet to prevent back firing which may sometimes occur as already indicated and is accompanied with a report of an undesirable character although otherwise harmless. Subject to these drawbacks 45 the nozzle may in some cases take the form shown in Fig. 6 which is useful on a small type of burner. In this modification a mixing chamber is dispensed with and the pipe 50 b communicates directly through a central hole into the conical shaped combustion chamber a^6 , it being understood that the areas of the inlet hole like that in Fig. 3 bear a proper relation to the nozzle orifice 55 for effecting the induction of outside air as already described with reference to the noz-

zle illustrated in Fig. 2. In conclusion it should be understood that although this relation of the areas is that the inlet area to the combustion chamber be less than that of 60 nozzle orifice, the nozzle orifice must nevertheless not be too large and the relative areas as taken from the drawing may be used as a criterion of what is suitable. It must also be understood that the mixing chamber a^2 65 which is shown in Fig. 2 in what we believe to be a very suitable form for the purposes of our invention may be modified considerably with various results or even be dispensed with entirely as shown in Fig. 6, and 70 that anything approaching a generally perforated disk between the mixing and the combustion chamber will not do.

Having thus described our invention, what we desire to claim and secure by Letters Pat- 75 ent in the United States is:—

1. A blow-pipe burner comprising in combination a combustion chamber forwardly converging, a mixing chamber behind the combustion chamber, a disk between the two, 80 said disk being provided with a central aperture and with a series of apertures surrounding said central aperture, and radially about equidistant from said central aperture and the periphery of said disk, whereby, 85 when a combustible mixture of air and carbureted air is ignited within the combustion chamber, the streams of burning gas are directed toward each other and away from the walls of said combustion chamber. 90

2. A blow-pipe burner comprising in combination a tapered combustion chamber converging to a discharge orifice, a mixing chamber behind the combustion chamber, a disk between the two, said disk being provided with a central aperture of less area than and coaxial with the discharge orifice, 95 there being an annular space equal at least in width to the width of the diameter of the disk aperture, surrounding said aperture, whereby a combustible mixture of air and carbureted air, ignited in said combustion chamber is directed away from the walls of said combustion chamber, by incoming 100 drafts of cooling air. 105

In testimony whereof, we affix our signatures, in presence of two witnesses.
